(57) **CLAIM**

The ornamental design for a lantern with speakers, as shown and described.

DESCRIPTION

FIG. 1 is a perspective view of the lantern with speakers, illustrating my new design;

FIG. 2 is a front elevational view of the lantern with speakers;

FIG. 3 is a rear elevational view of the lantern with speakers;

FIG. 4 is an elevational view of one side of the lantern with speakers;

FIG. 5 is an elevational view of the other side of the lantern with speakers; and

FIG. 6 is a top plan view of the lantern with speakers; and,

FIG. 7 is a bottom plan view of the lantern with speakers. The stipple shading and the straight line shading illustrate a contrasting appearance.

The broken lines immediately adjacent the shaded areas represent the bounds of the claimed design, while all other broken lines are directed to unclaimed portions of the article only; the broken lines form no part of the claimed design.

1 Claim, 6 Drawing Sheets
